DESIGN FOR A HAND GUN CARRIER RACK

Ivan L. Eastman, Bryan, Ohio, assignor to The
Aro Equipment Corporation, Bryan, Ohio, a
corporation of Ohio

Application October 9, 1933, Serial No. 49,427

Term of patent 7 years

To all whom it may concern:

Be it known that I, IVAN L. EASTMAN, a citizen
of the United States, and a resident of Bryan,
in the county of Williams and State of Ohio, have
invented a certain new, original, and ornamental
Design for a Hand Gun Carrier Rack, of which
the following is a specification, reference being
had to the accompanying drawing, forming part
thereof.

The figure is a perspective view of a hand gun
carrier rack showing my new design.

I claim:

The ornamental design for a hand gun carrier
rack substantially as shown.

Des Moines, Iowa, April 11, 1933.

IVAN L. EASTMAN.
